FIG. 1.

FIG. 2.

FIG. 3.

INVENTOR.
BARTON C. BRIDGHAM.
BY Chas. E. Townsend.
ATTORNEY.

UNITED STATES PATENT OFFICE.

BARTON C. BRIDGHAM, OF SAN FRANCISCO, CALIFORNIA.

CARD HOLDER.

Application filed April 20, 1921. Serial No. 462,823.

To all whom it may concern:

Be it known that I, BARTON C. BRIDGHAM, a citizen of the United States, residing at San Francisco, in the county of San Francisco and State of California, have invented new and useful Improvements in Card Holders, of which the following is a specification.

This invention relates to card holders and has for its object to provide a simple and inexpensive device of this nature to receive a card such as a registration certificate, and adapted to be attached in place to the dash of an automobile and operating in a manner to protect a card from entry of moisture or dirt. The device is capable of being constructed of extremely light material and hence is ideally suited for use as a holder for certificates of automobile registration where large numbers have to be shipped by mail.

One form which my invention may assume is exemplified in the following described illustration in the accompanying drawings in which Figure 1 shows a front elevation of a card holder, embodying my invention, arranged in place on the dash board of an automobile. Figure 2 shows a sectional view of the parts illustrated in Figure 1. Figure 3 shows a plan view of the tray.

The holder here shown is made in two parts, namely, a shallow tray (10) and an open-faced rectangular frame (11). The tray receives a card (12) and the frame (11) fits over the tray and surrounds the same. The tray is in the form of a shallow rectangular metallic piece with upturned marginal edges (13). The enclosing frame is made with side and end walls (14), which surround the edges of the tray, and inwardly extending beveled flanges (15) which overlie the card in the tray. Into each corner of the frame is inserted a screw or other fastening means (16) which extends through the tray and gives a support (17)—such as the dash of a vehicle for fastening the parts in position. The screws when tightened clamp the parts together so that the side and end walls of the frame contact tightly with the surface of the dash (17) and the inwardly extending beveled flanges (15) contact closely with the card (12) or with the transparent, water-proof covering (18) which is usually placed over the card.

The tray and frame are made of thin metal, preferably aluminum, or other light material. The device is easy and inexpensive to construct and affords complete protection to the card contained within by reason of the fact that the side and end walls of the frame and the upwardly extending beveled flanges (15) effectively keep out all dirt and moisture from the enclosed card. Likewise, by making these parts of aluminum, or other light material, they may be shipped by mail at small cost and hence the device is ideally suited for use by automobile registration boards of the various States, where large numbers are sent out by mail to the owners of vehicles.

Various changes may be made in the construction and arrangement of the several parts herein shown and described without departing from the spirit of my invention as disclosed in the appended claims.

Having thus described my invention, what I claim and desire to secure by Letters Patent is:—

1. A card holder comprising a shallow tray to receive a card, an enclosing frame, said frame having end and side walls to surround the tray and inwardly extending flanges overlying the card, a protective covering overlying the card and lying behind the flanges of the frame and means for fastening the parts in place on a supporting surface so that the edges of the end and side walls of the frame contact throughout their length with the supporting surface and the inwardly extending flanges compress the protective covering against the card in the tray whereby to prevent the entrance of moisture or dirt to the card.

2. A card holder comprising a shallow tray to receive a card, an enclosing frame therefor having end and side walls surrounding the tray and inwardly extending beveled flanges, and fastening means extending through each corner of the frame for clamping the parts in place on a supporting surface whereby the edges of the end and side walls of the frame contact with the supporting surface and the beveled flanges contact with the face of the card to keep out moisture and dirt.

3. A card holder comprising a shallow tray to receive a card, an enclosing frame having end and side walls surrounding the

tray and provided with inwardly extending beveled flanges, a transparent protective covering overlying the card in the tray and lying behind the beveled flanges of the frame and fastening means comprising a screw extending through each corner of the frame and tray for attaching the parts in place to a supporting surface whereby the edges of the side and end walls of the frame contact with the supporting surface, and the inwardly extending beveled flanges contact closely with the protecting covering in front of the card.

10

BARTON C. BRIDGHAM.
